DESIGN FOR AN OUTDOOR PLAYING CARD HOLDER

Sam Schindler, New York, N. Y.

Application August 18, 1944, Serial No. 114,932

Term of patent 3½ years

(CL. D34—5)

To all whom it may concern:

Be it known that I, Sam Schindler, a citizen of the United States, residing at New York, in the county of New York and State of New York, have invented a new, original, and ornamental Design for an Outdoor Playing Card Holder, of which the following is a specification, reference being had to the accompanying drawing, forming a part thereof.

In the drawing:

Fig. 1 is a perspective view of an outdoor playing card holder, showing my new design;

Fig. 2 is a rear perspective view and

Fig. 3 is a sectional view taken on the line 3—3 of Fig. 1 of the same.

I claim:

The ornamental design for an outdoor playing card holder, as shown.

SAM SCHINDLER.
